DESIGN FOR A BUILDING FRONT

Harry B. Barrett, St. Louis, Mo.

Application September 23, 1946, Serial No. 133,499

Term of patent 14 years

(Cl. D13—1)

To all whom it may concern:

Be it known that I, Harry B. Barrett, a citizen of the United States, residing at the city of St. Louis, State of Missouri, have invented a new, original, and ornamental Design for a Building Front, of which the following is a specification, reference being made to the accompanying drawing, forming a part thereof, in which Figure 1 is a top plan view of a building front embodying my new design, and Figure 2 is a front elevational view thereof.

I claim:

The ornamental design for a building front, substantially as shown.

HARRY B. BARRETT.
